UNITED STATES PATENT OFFICE.

ROBERT E. VAN PATTEN, OF JEROME, MICHIGAN.

COFFIN.

SPECIFICATION forming part of Letters Patent No. 718,803, dated January 20, 1903.

Application filed April 16, 1902. Serial No. 103,197. (No model.)

To all whom it may concern:

Be it known that I, ROBERT E. VAN PATTEN, a citizen of the United States, residing at Jerome, in the county of Hillsdale and State 5 of Michigan, have invented new and useful Improvements in Coffins, of which the following is a specification.

This invention relates to a composite coffin; and one of the objects thereof is to provide an 10 efficient means for preventing the deterioration or crumbling of the coffin and to provide means whereby the plastic material will be held together.

In order to clearly appreciate the advantages of my device, reference should be had 15 to the accompanying drawings, in which—

Figure 1 is a perspective view of the frame, the plastic portion being shown in section. Fig. 2 is a vertical longitudinal sectional view 20 through the coffin, part of the plastic material being cut away to show the construction of the skeleton frame. Fig. 3 is a transverse sectional view through the same. Fig. 4 is a detail perspective view showing how the 25 braces are joined, and Fig. 5 is a perspective view showing the split ends of one of the braces preparatory to being folded.

In carrying out the invention I first make a skeleton frame, which forms the mold 30 around which is caused to set the plastic material forming the coffin.

The reference-numerals 1 and 2 designate two parallel longitudinally-extending bars, at the extremities of which are vertical extensions 3 and 4 to form the ends of the frame, the extremities of the vertical extensions 3 and 4 being split longitudinally, as at 5, for a portion of their length to provide fingers, which may be bent in opposite directions for 35 the purpose of holding the lateral frame thereon to be referred to hereinafter. Arranged intermediate the ends of the bars 1 and 2 and secured thereto are parallel, horizontal, and transversely-arranged brace-bars 6 and 7, which also have vertically-extending ends 8 and 9, which are of approximately the same 40 length as the extensions 3 and 4 of the bars 1 and 2. The ends 8 and 9 are also split, as at 10, in a manner similar to the ends of the 45 extensions 3 and 4, and also designed for the purpose of holding the frame on the top of

the bars to add rigidity to the structure. It will be noticed that these extended ends 8 and 9 form the side brace-bars for the structure, while the ends 3 and 4 add strength to the ends 55 of the structure. In order that the bars may be held in their relative position and to add rigidity and strength to the coffin, I provide a horizontally-arranged flanged brace 11, which extends around the top of the structure and is 60 provided with a lateral flange 12, which extends outwardly, the entire brace 11 being in the form of an angle-iron and is approximately rectangular. In adjusting the brace 11 the vertical portion thereof is seated between the 65 split ends of the vertical extensions 3 and 4 and the split ends of the vertical extensions 8 and 9 of the bars 6 and 7. The brace is then tied in by bending the fingers 13 of the split ends 1 and 2 on one side of the brace 11 and 70 over the flange 12 and by bending the other finger of the flange 12 in the opposite direction. The fingers 14 of the bars 8 and 9 are likewise bent over the brace 11 to securely tie it to the bars 1 and 2 and 5 and 6. Intermediate the ends of the extensions 8 and 9 are arranged longitudinal side braces 15 and 16, which are connected to the vertical extensions of the bars 6 and 7 by bending the 75 fingers 16^a and 17 thereof in opposite directions and thence around the extended ends just referred to.

It will of course be understood that the ends of the bars 15 and 16 are split in a manner similar to the ends of the bars 1 and 2, so 85 that the fingers can be caused to embrace the extended ends 8 and 9. The frame thus formed constitutes the form of pattern of the coffin, and the plastic material is molded around the same to complete the body portion. A top is provided to the coffin, which 90 comprises a frame 18, approximately rectangular, but conforming to the contour of the brace 11 and having a downwardly-projecting flange 19, which is adapted to fit over said 95 brace when it is desired to seal the coffin. The top or cover of the frame 18 has secured to the end portions thereof two bowed-shaped bars 19^a and 20, which extend longitudinally of the frame and are provided with split ends 100 21, the edge of the frame fitting in the slit, so that the fingers 22 and 23 of the bars 19^a

and 20 may be bent in opposite directions and over the flanged frame 18 to tie the bowed braces or bars in place. A transverse bar 24 is arranged intermediate the ends of the frame 18 and is also bowed to extend over the bowed bars 19^a and 20. This bar 24 is also provided with split ends 25 and is connected intermediate the ends of the frame by bending the fingers formed by the slit 25 in opposite directions to embrace the side bars of the frame 18. By forming the bars 19, 20, and 24 slightly bow-shaped a slightly oval appearance or shape is given to the coffin. The plastic material can be formed over the top, completing the device. The top may be secured upon the coffin proper by plastic or other means, making it practically an airtight or waterproof receptacle for the body.

It will of course be understood that I reserve the right to use any material for the plastic composition which may seem best adapted for the purpose and that any form of frame may be employed to suit the prevailing custom without departing from the spirit 25 of this invention.

It will be apparent from the foregoing that a coffin constructed in accordance with the above will not be liable to become broken or easily deteriorate, inasmuch as the frame will 30 materially assist in holding the component parts in a homogeneous mass.

Having thus described my invention, what I claim, and desire to secure by Letters Patent, is—

35 1. In a skeleton frame means for securing the parts together comprising split ends to

form fingers adapted to be bent in opposite directions to unite the parts.

2. A frame for a coffin comprising longitudinal bars and transverse bars each of the 40 bars having vertically-extending ends and each bar being provided with a split extremity, a brace extending around the top of the bars and fitting in the slotted portions thereof, said slotted portions having fingers which are 45 bent around the frame to secure it to the bars.

3. A skeleton frame comprising longitudinal bars and transverse bars having vertical extensions provided with slotted ends, a brace extending around the top of the bars and 50 having an outwardly-extending flange, the fingers formed by the split ends being bent in opposite directions to embrace the bars and fit over the outwardly-projecting flange.

4. A skeleton frame comprising longitudinal bars and transverse bars having vertical extensions provided with slotted ends, a brace extending around the top of the bars and having an outwardly-extending flange, the fingers formed by the split ends being bent in opposite directions to embrace the bars and fit over the outwardly-projecting flange, and flanged side bars connecting the vertical extensions of the transverse bars and also having oppositely-bent fingers to embrace the 60 side bars.

In testimony whereof I affix my signature in presence of two witnesses.

ROBERT E. VAN PATTEN.
